UNITED STATES PATENT OFFICE

ADDISON C. ARMSTRONG, OF BALTIMORE, MARYLAND, ASSIGNOR TO CAMPBELL METAL WINDOW CORPORATION, OF BALTIMORE, MARYLAND, A CORPORATION OF MARYLAND

RADIATOR SUPPORT

Application filed January 28, 1928. Serial No. 250,115.

When operating under Campbell Patent No. 1,286,210 of May 14, 1918, (which relates to a radiator bracket attached to the sill of a metal window) it has been found advantageous to form a hook near the edge of the sill about on a line with the inner face of the finished wall below the window. The radiator bracket is connected with this hook.

A practical difficulty has arisen in connection with such a construction owing to the fact that there is apt to be a substantial variation in the thickness of various portions of the masonry walls in a given building. Because of this variation it has been found that where the sill and stool are either formed in one piece or are fabricated and connected together before the window is installed, the hook from which the radiator bracket is to be suspended may be substantially out of line with the inner face of the finished wall below the window. To avoid this difficulty it is sometimes necessary to make the sill separate from the stool, and fabricate the stools after the window is in place, a separate stool being made for each window according to measurements taken on the job. This of course is expensive.

When providing the bracket for a radiator it must be borne in mind that the pull of the radiator, while primarily directed downwardly, has a resultant pull (due to a turning moment) tending to pull the top of the bracket out from the wall. I have found that one of the highly important advantages of connecting the radiator bracket to the window sill is due to the fact that this resultant pull is fully taken care of if the bracket and sill are connected together, because the anchorage of the entire window-frame resists the strain referred to. At the same time the bracket is definitely located in a vertical position relative to the window even though the vertical strain is taken up by the wall itself. Bearing these factors in mind, I have found that the difficulties heretofore referred to can be overcome by providing a hook on the underside of the sill member (which term is intended to refer to an integral sill and stool and also to a stool made as a separate piece from the sill) which hook is positioned substan-

tially back of the inner face of the finished wall. This hook is so arranged that a radiator bracket member can be interlocked with it in such a way as to prevent such member from moving inwardly in relation to the sill, and preferably the interlocking is so arranged that the two cannot become separated unless the inner part of such member is raised. However, it is essential that such radiator bracket member be readily connected to such hook after the window is in place and should be readily removable therefrom.

The radiator bracket member is adapted to interlock with such hook on the underside of the sill, and extends over a portion of the masonry wall and preferably is supported against downward movement near the inner face of the masonry wall. The radiator bracket proper depends from this member. The horizontal member and the bracket may be made integral but I prefer to make them separately turning up a lip on the horizontal member to which the radiator bracket proper is hooked.

By the construction described, the window can be fabricated with the sill members of such width that they will overlie the edge of the finished wall and if the walls vary, this will result in variations in the degree to which the sill member overhangs the wall, which is of minor importance. After the walls are finished and the plaster is in place, variations in the thickness of the wall can be taken care of as regards the radiator supports, by varying the length of the horizontal bracket members. If such members are made separate from the brackets proper, no special fabrication or measurement will be necessary, for the workman installing the radiator brackets can carry around an assortment of these pieces of different lengths and insert the ones that are appropriate for each window. These pieces are very inexpensive to make and there is little loss in maintaining a stock of assorted sizes. If the horizontal member and bracket are made integral, either a stock of brackets with horizontal portions of varying lengths must be provided, or the brackets can be fabricated after measurements are taken.

this invention are shown in the accompanying drawings in which Fig. 1 is a sectional view through a wall and window-frame showing the device in operation with a radiator in place; Fig. 2 is a section on line 2—2 of Fig. 1 but showing the radiator removed, and Fig. 3 shows a modified structure.

In the example illustrated in Figs. 1 and 2, the sill 3 has made integral with it a stool 4 which extends out over the radiator as indicated at 6. Other portions of the window-frame are illustrated in the drawing, but as they form no part of the present invention, they are not further described.

15 The sill 3 rests on a wall of masonry or similar material designated by the numeral 8, and 10 indicates the plaster face of the wall. Welded to the underside of the sill 3 is a hook-shaped member 12. This prefer-
20 ably extends for substantially the length of the sill and assists in supporting the stool portion 4 of the sill. A horizontal member 14 is adapted to interlock with member 12 as shown in Fig. 1. The inner edge of member 25 14 is turned up to form a lip 16 and near the inner edge, member 14 may either rest directly on the masonry of the wall or a shim 18 may be inserted. The member 14 may be substantially the length of the radiator, or as shown 30 in Fig. 2, one member 14 may be used for each radiator bracket. It will be noted that the member 14 can readily be removed at any time, and therefore does not need to be installed until after the window-frame is in 35 place and the plaster 10 is finished. At that time the workman installing the job can go through the building with an assortment of pieces corresponding to member 14 and at each window can insert the appropriate size 40 so that the lip 16 is substantially in line with the inner face of the plaster 10. The radiator bracket has a vertical portion 20 adapted to lie flat against the plaster 10, which portion is bent over at the top to form a hook 22. As 45 here illustrated, the bracket proper is made in one piece, having a radiator supporting portion 24 which is bent inward from the portion 20.

In the form of device shown in Fig. 3 the 50 horizontal member 14' is made integral with the vertical portion 20' of the bracket.

By either of these arrangements it is readily possible to fabricate a sill and stool of an appropriate width and then, due to the fact 55 that the horizontal member is readily removable, the radiator brackets can be installed accurately after the wall is finished and plastered. Even if the horizontal member were 60 not readily removable, the structure shown herein would be highly advantageous because of the fact that the weight of the radiator is carried by the masonry wall, so that there is no tendency for the sill to be dragged down, 65 but at the same time the radiator supports

are held located in proper position due to their connection with the sill.

What I claim is:

1. In combination with a metal sill member built into a wall, a hook on the underside 70 of the sill member removed back from the inner face of such wall, a readily removable member adapted to engage said hook, and when so engaged to be held against inward movement, and a radiator bracket adapted to 75 lie against the inner face of the wall supported by and connected with said removable member.

2. A structure as specified in claim 1, in which the radiator bracket and said removable member are separable. 80

3. A structure as specified in claim 1 in which said hook has a downwardly extending portion adapted to engage the upper edge of the readily removable member and the structure comprises a horizontal member adapted to engage the underside of said removable member whereby said removable member will be held locked in said hook until the free end thereof is lifted. 85

4. In combination with a metal sill member built in a wall, a substantially horizontal support member resting on the wall below the sill and spaced away from the sill, radiator supports connected with such horizontal 95 member so that the weight of the radiator is carried directly by the wall, and means for connecting such horizontal member with the sill to hold such horizontal member in place on the wall. 100

5. The combination with a stool structure having a depending stiffening flange along its inner margin, of a supporting member separate from the flange and located beneath the stool and behind the flange, and a hanger bracket hung from said member. 105

6. The combination with a stool structure having a depending stiffening flange along its inner margin, of a supporting member separate from the flange and located beneath 110 the stool and behind the flange and having an upstanding hook portion behind said flange, and a hanger bracket having a hooked upper end passing between the flange and member and hooked over the upstanding 115 hook portion of the supporting member.

7. The combination with a wall structure including a stool that extends inwardly beyond the wall structure, of a supporting member beneath the stool and behind its inner 120 end, said supporting member resting on the wall structure beneath the stool, and a hanger bracket suspended from the supporting member.

8. The combination with a stool structure having a depending stiffening flange along its inner edge portion, of a supporting plate separate from the flange and secured to the stool structure behind the flange, and a hanger bracket hung from the plate. 125

9. The combination with a stool structure having a depending stiffening flange along its inner edge portion, of a depending supporting plate secured to the stool structure behind the flange and having an upstanding hook margin spaced from the flange, and a hanger bracket having a hooked upper end suspended from the hook margin, said bracket depending below the stool structure.

5 ADDISON C. ARMSTRONG.

9. The combination with a stool structure having a depending stiffening flange along its inner edge portion, of a depending supporting plate secured to the stool structure behind the flange and having an upstanding hook margin spaced from the flange, and a hanger bracket having a hooked upper end suspended from the hook margin, said bracket depending below the stool structure.
